UNITED STATES PATENT OFFICE

170,080

BAG

Rajean M. Codish, New York, N. Y.

Application April 5, 1952, Serial No. 19,209

Term of patent 7 years

(Cl. D87—3)

To all whom it may concern:

Be it known that I, Rajean M. Codish, a citizen of the United States, residing at New York, in the county and State of New York, have invented a new, original, and ornamental Design for a Bag, of which the following is a specification, reference being had to the accompanying drawing, forming a part thereof.

In the drawing:

Fig. 1 is a perspective view of the bag of my design, showing it in its open position;

Fig. 2 is a top view thereof, showing the bag closed;

Fig. 3 is a front elevational view of the same; and

Fig. 4 is a side elevational view thereof.

Fig. 5 is a side elevational view similar to

Fig. 4, showing the bag empty and in a collapsed condition.

I claim:

The ornamental design for a bag, substantially as shown.

RAJEEAN M. CODISH.
